UNITED STATES PATENT OFFICE.

ERNEST OCTAVE BARETTE, OF MONTREAL, QUEBEC, CANADA.

GARTER.

1,207,265.

Specification of Letters Patent.

Patented Dec. 5, 1916.

Application filed February 12, 1915. Serial No. 7,741.

To all whom it may concern:

Be it known that I, ERNEST OCTAVE BARETTE, a subject of the King of Great Britain, residing at No. 301 St. James street, 5 Montreal, Province of Quebec, Canada, have invented certain new and useful Improvements in Garters; and I do hereby declare that the following is a full, clear, and exact description of the invention, such as will 10 enable others skilled in the art to which it appertains to make and use the same.

The object of my present invention is a new and improved garter which adjusts itself automatically to the thickness of the 15 leg and also to all the movements of the leg of the wearer.

A further improvement of my new garter consists in attaining the above mentioned purpose without forming folds in any part 20 of the ribbon of the garter and without exerting different stress on the different sides of the garter.

The essential features of my invention, which allow the obtaining of such advantages, are the arrangements of articulating 25 joints in the garter, and of a triangular loop at the top of the members holding the stockings, said triangular loop being formed by passing the part of the ribbon near the 30 one end of same through eyelets at the other end of the ribbon and at the top of the member holding the stocking, and then back to the main part of the garter.

In order to more clearly disclose the construction, operation, and use of the invention, reference should be had to the accompanying drawings forming part of the present application.

Throughout the several figures of the 40 drawings like reference characters designate the same parts.

In the drawings: Figure 1 shows my new garter in the position which it assumes in the case of a comparatively thick leg; Fig. 2 45 shows it in the position for a thinner leg; and Fig. 3 shows it in practical use as put on a leg and holding a stocking.

My improved garter is made preferably of an elastic ribbon 1 one end of which 50 forms a loop 2 for the rough adjustment to the thickness of the leg of the wearer, which is done by passing first the ribbons between the inner and the two outer stays or legs of a three-legged eyelet 3, then through a two-legged eyelet 4 and then fastening the end 55

itself on the middle-stay of the eyelet 3. The other stay of the two-legged eyelet 4 bears a flap 5 to be fastened on a flap 6 by means of a snap button 7 such as is commonly used for gloves and other clothing. 60 On the other side of the garter the ribbon 1 on a reinforcing cross-stay 8 bears a knob 9 and the ribbon passes through the rectangular opening of a two-legged eyelet 10, which is fastened on the aforementioned flap 6. 65 Then it passes downwardly through the rectangular opening of another two-legged eyelet 12 fastened on the members holding the stockings, and finally returns again upwardly to the main part or belt of the 70 garter on which it is fastened with a suitable eye 13 on the knob 9, so as to allow a swinging around this knob.

The members for holding the stocking may be of any suitable construction; in the 75 example shown they consist of a short ribbon 14 with a button 15 at its end and a bent-wire snare 16, the upper broader part of which allows the passing through of the head of the button with the upper brim of 80 the stocking 17 to be held, while the lower end of this snare is made narrower so as to prevent the head of the button and the brim of the stocking from slipping out.

In the use of my garter it is first adjusted 85 roughly to the thickness of the leg of the wearer by a corresponding adjustment of the loop 2; then it is passed around the leg and the snap-button 7 is closed; then the brim of the stocking 17 is fastened by putting 90 it over the button 15 and slipping both together into the narrow part of the snare 16, so that the whole has a position as indicated in Fig. 3. If the leg is somewhat thicker and the tension of the stockings not very 95 great, then the self-adjusting parts of my garter will form a flat triangle such as shown in Fig. 1; if the leg is thinner and the tension of the stocking greater, which, for instance, will happen if the garter is put on 100 the leg at a somewhat higher place than in the first case, then the self-adjusting parts of my garter form a more prolonged or pointed triangle such as shown in Fig. 2. The articulations formed by the snap-buttons 7 and by the knob 9 together with the free sliding of the ribbon 1 through the eyelets 10 and 12 insure a perfect adjustment of 105 my garter to the requirements of the special case, so that the forming of folds in it, un- 110 116

due stress at the one or the other side of same and pressing on the leg of the wearer are avoided.

It is thought that the construction, operation, and use of the invention will be clear from the preceding detailed description.

Changes may be made in the construction, arrangement, and disposition of the several parts of the invention without in any way departing from the field and scope of the same, and it is meant to include all such within this application wherein only a preferred form has been disclosed.

Having thus fully described my invention, what I claim as new and desire to secure by Letters Patent is:

1. In a garter, a main belt having an eye at one end and a knob on which said eye fits detachably and pivotally, forming a loop, 20 in combination with an eyelet, through which said loop freely slides, at the end of said loop remote from said knob and eye, a flap attached to this eyelet, a two-legged eyelet and a three-legged eyelet engaging 25 the other end of said belt for tightening or loosening the latter, a flap connected to one of these two eyelets, a snap-button detachably and pivotally connecting these two flaps together, an eye on the lower part of 30 said loop, through which the latter freely

passes and hose supporting means suspended from this latter loop, said knob and snap-button permitting pivotal motion of the parts connected thereby as set forth.

2. The main belt of a garter having one 35 end detachably and pivotally connected to a point on said belt to form a loop, the other end being provided with means for taking up and expanding said belt, an eyelet through which said loop passes freely, de- 40 attachable and pivotal means for connecting said expansible means to said eyelet, another eyelet through which the lower part of said loop passes freely and hose suspending means depending from this latter eyelet, the 45 said freedom of movement of the loop of the belt through the latter two eyelets and the pivotal attachments at two points as above stated permitting said loop to take the form of a triangle having automatically adjustable sides and being adapted to descend and assume more acute angles when the belt is tightened.

In witness whereof I have hereunto set my hand in the presence of two witnesses.

ERNEST OCTAVE BARETTE.
